United States Patent Office.

W. B. COATES, OF PHILADELPHIA, PENNSYLVANIA, ASSIGNOR TO DAVID LYMAN, OF MIDDLEFIELD, CONNECTICUT.

Letters Patent No. 77,356, dated April 28, 1868.

IMPROVED STARCHING-APPARATUS.

The Schedule referred to in these Letters Patent and making part of the same.

TO ALL WHOM IT MAY CONCERN:

Be it known that I, W. B. COATES, of the city and county of Philadelphia, in the State of Pennsylvania, have invented a certain new and improved Machine or Apparatus for Starching Clothes; and I do hereby declare that the following is a full and exact description thereof.

My apparatus encloses the starch in a portable case or vessel having a soft bottom, which serves as a strainer. On rubbing the device over the surface of the shirt-bosom or other clothing to be treated, starch is applied in the desired quantity with great uniformity.

I will first proceed to describe what I consider the best means of carrying out my invention, and will afterwards designate the points which I believe to be new therein.

The accompanying drawings form a part of this specification.

Figure 1 is a side elevation.

Figure 2 is a plan view.

Figure 3 is a central vertical section.

Similar letters of reference indicate like parts in all the figures.

A is the main body or easing, made by preference of any hard or fine-grained wood which will not stain the starch, such as maple or beech wood.

B is a cork, fitting in the orifice a, and b is a cap, of brass or other suitable material, which fits over and forms a convenient handle or holding-piece, and stiffens and supports the connection of the cork to the ease.

C is a semispherical bag, of cotton-duck or other woven or knitted or felted fabric. It is firmly secured by its edges to the edges of the easing A, by means of twine, cord, copper wire, or other suitable material, wound around in the groove a', as represented.

D is a piece of tape, fastened by copper tacks or otherwise around the edge, forming a nice finish, and being provided with a loop, d, by which the device may be conveniently hung upon a nail or other object when not in use.

The operation of my invention will be readily understood. The plug B being pulled out, a quantity of semi-fluid starch is introduced in the aperture A, and the bag C is partially or entirely filled. The plug B is now inserted in its place, and the device, after having been manipulated for a short time to insure a uniform permeability of the bag, is ready to be applied successively to each of the shirts or other articles, and passed more or less rapidly and pressed down more or less forcibly on the surface. The goods, after having been thus starched, may be manipulated in the ordinary manner, to better distribute the starch, or may be dried without any such handling, as may be preferred. The starcher may rest on any convenient surface in the brief interval between the several operations in treating a series of shirts or other articles, but should be emptied, washed, and hung up by the loop d at the close of each day's work.

The stopper can, if preferred, be made without cap and screw, but rounding at top, and with a flange to rest on A.

I call this a starching-device, but it may be used for other purposes. I propose to use it sometimes for introducing indigo to the clothes, or to the water in which clothes are to be rinsed.

Having now fully described my invention, what I claim as new, and desire to secure by Letters Patent, is as follows:

I claim the starching-device herein described, consisting of a rigid vessel, A, closing-means B, and a strainer, C, constructed and adapted to operate substantially in the manner and for the purpose herein specified.

W. B. COATES.
